UNITED STATES PATENT OFFICE

JOHN E. OSTLINE, OF BERWYN, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

TELEPHONE SYSTEM

Application filed May 7, 1931, Serial No. 535,589. Renewed September 9, 1932.

The present invention relates to telephone systems in general, but is concerned more particularly with telephone systems in which 5 automatic switches are used to set up connections in response to numbers dialled by calling subscribers; and the main object, broadly stated, is the production of new and improved circuit arrangements in an automatic telephone system for simplifying the relay apparatus of the various individual switches so as to reduce the cost of the automatic equipment and to introduce such new operating characteristics as are found to be desirable or conducive to general economy in plant 10 equipment.

General description

It is common practice in automatic telephone systems to provide each of the switches 20 successively employed in a telephone connection with sufficient relay apparatus to enable it to receive impulses transmitted thereto from a calling line and perform its necessary functions. In order to make possible a more economical trunking network in multi-office systems, and in order to render it unnecessary to adjust the control relays of the automatic switches to respond to the widely varying 25 characteristics of the subscribers' lines from which the controlling impulses are received, and for other purposes of a similar nature, automatic telephone systems have been developed employing register senders arranged to 30 register the digits transmitted from the subscribers' lines and to retransmit them to the automatic switches, making the necessary 35 translation in the office-designating digits in accordance with the most economical layout 40 of interoffice trunks and in accordance with the office originating the call.

The present invention is concerned with 45 improvements in a system employing register senders for the purposes above outlined. One feature of the invention relates to the provision of cooperating circuit arrangements in the register senders and in the automatic switches, whereby operating impulses 50 may be transmitted over one talking conductor directly from a register sender to the magnets of the automatic switches. It is a

further feature that the other talking conductor is used to control a relay in each of the automatic switches which corresponds generally to the so-called slow-acting series relay, one of which is ordinarily employed 55 in each automatic switch to control the change-over operation at the end of a received digit.

An additional feature of the invention has to do with circuit arrangements in the automatic selectors, cooperating with circuit arrangements in the register senders so that a selector is caused to search over a group of 60 trunk lines repeatedly when it finds all trunk lines in the group busy, this being accomplished by causing a selector to be automatically restored to normal position when it finds all trunk lines in a group busy and by causing the register sender to repeat the previous digit so as to reoperate the selector to 65 again bring it into association with the desired group of trunk lines.

A feature incidental to the preceding one has to do with an arrangement in the register sender for recording the number of 70 times a digit is repeated to a selector and for stopping the repeating operation when a predetermined number of repetitions of the same digit have occurred. In such a case, 75 the operated switches are released and the calling subscriber is informed by a tone signal, hereinafter termed a verification tone, 80 that he cannot obtain the number dialled.

According to a further feature, each connector is provided with a sequence switch 85 which is arranged to be stepped over one of the talking conductors to transfer the operating circuit from the primary magnet to the secondary magnet and to shift the connector into testing position at the end of the 90 secondary movement, all incidental to the transmission to the connector of the tens and units digits. A special feature of this arrangement is that two additional control impulses are transmitted by the register sender 95 to advance the sequence switch following its advance into the first testing position, advancing the sequence switch successively into its second and third test positions, whereby 100 not only the busy or idle condition of the

line is determined, but a special test condition is obtained in case the terminals reached by the connector wipers have no line connected thereto. In any case, the condition of the line as determined by the tests made is recorded in the register sender which, before becoming automatically disconnected, relays the condition of the called line to the primary unit located in the primary trunk of the connection, whereat arrangements are made for sending back any one of three tones to the calling line to inform the calling subscriber as to whether the line is busy, idle, or disconnected from the terminals, the tone indicative of the last condition being the hereinbefore-mentioned verification tone.

A feature of the arrangement above mentioned is that arrangements are provided in the primary unit for automatically releasing all of the operated numerical switches of a connection responsive to the test condition indicating that the called line is busy and to the test condition indicating that the connector has been set on terminals not connected to a called line.

It is a further feature of the arrangement that talking current is supplied to both lines of an established connection from the primary unit of the primary trunk in use, except in interoffice connections, wherein talking current is supplied to the called line from the incoming selector repeater in the called office. A special feature of this arrangement is that the front and back bridges of the primary unit are disconnected under the control of the register sender when a connection has been set up in which talking current is not required or desired from the primary unit, thereby extending the calling line metallically and without bridges to the called line. This is advantageous, as for example when a connection is set up to a trunk line extended to the switchboard of a toll operator, as is well known.

An additional feature of the system disclosed herein is that when an interoffice connection is being set up the controls exercised by a register sender are repeated by an incoming selector repeater located in the distant office, and that this selector repeater relays the necessary test and supervisory conditions back toward the calling end of the connection. The incoming selector repeater supplies talking current to the called line.

Additional objects and features of the invention relate to the production of economical and commercial circuit arrangements for carrying out the objects and features hereinbefore enumerated and for giving the necessary supervision, as will become more apparent as the description progresses.

Description of drawings

Referring now to the accompanying drawings comprising Figs. 1 to 6, they show by

means of the usual circuit diagrams a sufficient amount of apparatus in a telephone system embodying the features of the invention to enable the features to be understood. Figs. 1 to 3, which should be placed end to end, show switching equipment which may be involved in a connection from the line of substation A, Fig. 1, to the line of substation B, Fig. 3; Figs. 4 and 5, which should be placed in order below Fig. 1, show one of the register senders used to control the setting up of connections; and Fig. 6 shows the trunk circuit TC interposed between an incoming trunk line and the jack J located at the switchboard of an "assistance" operator.

Fig. 1 shows the office selector OS which is accessible to the lineswitch LS of the line of substation A by way of the trunk line comprising conductors 106-108. The primary unit PU, including relays 109 to 117, is inserted in the trunk line between conductors 106-108 and 124-126. The director selector DS is individual to the primary unit PU and has access to a group of directors or register senders, one of which is the director or register sender shown in Figs. 4 and 5. This director selector is of the same rotary type of mechanism as the ordinary rotary lineswitch, such as LS. The wipers 152-158 of the director selector DS are arranged to be driven in a forward direction only over a semi-circular bank of contacts and are arranged to be advanced upon the back stroke of the magnet 151. The office selector OS is a switch of the regular Strowger type, having wipers 179-181 which are arranged to be raised opposite the desired level of contacts by the vertical magnet 178 and to be rotated over the contacts in the desired level by the rotary magnet 174. The release magnet 175 is provided for the purpose of restoring the selector to its normal position. The off-normal contacts 170 and 177 close responsive to the shaft of the selector being raised from its normal position and are again opened when the selector is restored to its normal position. The overflow contacts 176 are arranged to be operated by a cam carried by the shaft whenever the wipers are driven over the last set of bank contacts in a level. The circuits of the lineswitch LS are well known and have not been illustrated.

Fig. 2 shows the thousands selector TH.S and the hundreds selector HS. The thousands selector TH.S is an incoming repeater terminating the incoming two-conductor trunk (185, 187), which is one trunk of the group accessible to the office selector such as OS, Fig. 1. Mechanically, the switches TH.S and HS are each similar to the switch OS, Fig. 1.

The connector C, Fig. 3, is similar mechanically to the selectors except that it is provided with a sequence switch SE which has wipers 310 and 313 arranged to be operated

one step upon each energization of operating magnet 311. The circuit-closing contacts 312 and 314 are arranged to be closed by a cam action at the same time the wipers 310 and 313 are driven onto the fifth associated contacts. The release magnet 308, which is the release magnet of the connector C, has an extension arm mounted on its armature and arranged to remove the holding dog (not shown) to bring about the release of the sequence switch SE.

Referring now to Figs. 4 and 5, the director shown therein comprises the digit registers A-T, B-U, TH, and H, Fig. 5; the translator switch TS which is arranged to assume a position assigned to the called office as indicated by the composite setting of wipers 512 and 517 of the registers A-T and B-U; and the counting switch CS which is arranged to count the impulses in the office-code digits and numerical digits sent out under the control of the translator switch TS and the registers A-T to H, respectively.

The input control switch ICS, Fig. 4, is arranged to distribute the first four series of incoming impulses to the registers A-T, B-U, TH, and H, respectively, and to distribute the fifth and sixth series of impulses to the registers A-T and B-U, which have become released in the meantime.

The output control switch OCS, Fig. 5, is arranged to render the register wipers successively effective to control the counting switch CS during the retransmission of impulses, and to control the transmission to the primary unit of the various switch-through impulses, depending upon the test condition received from the switch train at the time the switch-through operation is performed.

Mechanically, each of the switches ICS, OCS, A-T, B-U, TH, H, and CS is arranged to be operated in a forward direction only and upon the back stroke of the associated magnet. Each wiper of one of these switches has a semi-circular bank of eleven contacts, as shown. The translating switch TS is of similar construction, having eight wipers, 1 to 8, which are arranged to be driven over a semi-circular bank of contacts by the operating magnet 535, being advanced upon the back stroke of this magnet. There are assumed to be twenty-five sets of contacts in the bank of the translator TS, although this number is purely arbitrary.

The repetition controller RC, Fig. 4, has a wiper 429 which is arranged to be advanced one step over the associated contact bank each time the operating magnet 426 energizes, and to be restored to normal each time release magnet 427 operates.

Throughout Figs. 4 and 5, there are a number of contact pairs associated with the various switches and labeled "ON". In each case, these contacts are normally in the posi-

tion shown in the drawings and are arranged to close when the associated switch is moved from its normal position.

Detailed description

The invention having been described generally, a detailed description of the operation of the apparatus shown will now be given. For this purpose it will be assumed that the subscriber at substation A, Fig. 1, desires to converse with the subscriber at substation B, Fig. 2, whose number is assumed to be 45-1234, the digits 4 and 5 indicating the office in which the desired line terminates, and the digits 1, 2, 3, and 4 indicating the designation of the called line within the office.

Call from substation A to substation B

When the subscriber at substation A removes his receiver he thereby closes a circuit over line conductors 101 and 102 for bringing about the operation of the lineswitch LS and the grounding of test conductor 103 so as to render the line busy in the banks of the connector switches having access to it. The wipers 103-105 of the lineswitch LS are advanced step by step in search of an idle trunk line. It will be assumed that the trunk line comprising conductors 106-108 is the first one found to be idle and that it is, therefore, seized. When this trunk line is seized, line relay 111 in the primary unit PU, which is normally bridged across the conductors 106 and 108 of the trunk line by way of contacts of relays 116, 109, and 110, operates over the calling line and closes a circuit for the slow-release relay 112. Upon operating, relay 112 places ground potential on conductor 107 at its upper armature by way of contacts of relays 109 and 110, thereby establishing a holding circuit for the lineswitch LS.

Seizing an idle director

At its lower armature, line relay 111 connects test wiper 155 and operating magnet 151 together through the self-interrupting contacts of the operating magnet, thereby initiating the hunting movement of the director selector. The connection between wiper 155 and magnet 151 includes armature 144 and its resting contact, armature 135, inner lower armature of relay 113, and armature 142, in addition to the lower armature of relay 111. The wipers 152-158 of the director selector DS are now driven step by step in search of an idle director, busy directors being marked by ground potential on the corresponding test contacts.

When release relay 112 operates as above mentioned, it places ground potential on locking conductor 147 at its inner upper armature, thereby closing a circuit by way of armatures 134, 149, and 141 for switching relay 116, which is arranged to operate and switch the connection through to a director as soon as an idle one has been found by the

director selector DS. The battery supply for relay 116 is obtained through the operating magnet 151 of the director selector DS through armature 142, inner lower armature 5 of relay 113 and armature 135. As a result, relay 116 does not operate as long as the free terminal of operating magnet 151 is maintained grounded by test wiper 155. As soon, however, as an idle director is reached, test 10 wiper 155 encounters the ungrounded test contact of the idle director and the operation of magnet 151 ceases. At this point, relay 116 operates in series with magnet 151, but magnet 151 does not operate at this time be- 15 cause of the high resistance of relay 116.

When relay 116 operates, it connects wipers 153 and 152 of the director selector DS to the incoming talking conductors 106 and 108 at its upper and lower armatures, at the 20 same time disconnecting line relay 111 from conductors 106 and 108; at its inner upper armature and at armature 146 it connects wipers 157 and 158 of DS to conductors 124 and 126 of the selector OS, at the same time 25 disconnecting these conductors from the back-bridge battery-feed relay 117; at armature 145 it opens a point in a local circuit for relays 113 and 114 and connects these relays to switch-through wiper 154; at its 30 inner lower armature it connects relay 115 and the upper winding of relay 114 to the switch-through wiper 156; and at armature 144 it opens a point in the test circuit and connects test wiper 154 to the winding of 35 release relay 112, thereby preparing a holding circuit for release relay 112, so that the relay will be held operated from the seized director after line relay 111 has fallen back.

In the seized director (assumed to be the 40 director shown in Figs. 4 and 5), line relay 402, which is bridged across conductors 160, extending from the bank contacts on which wipers 152 and 153 are now standing, energizes over the calling line by way of conductors 106 and 108 and the upper and lower armatures of relay 116 of the primary unit PU. Upon operating, line relay 103 closes a circuit for release relay 403 which operates and prepares the director for operation. 45 This preparation consists mainly in opening points in circuits of various restoring circuits and in preparing locking circuits for the relays. In addition, the impulse circuit over which the register sender is operated is prepared at the inner upper armature of relay 403, while at the upper armature of relay 403 ground potential is placed on conductor 162, thereby closing a holding circuit by way of wiper 155 and the operated armature 144 50 for release relay 112 of the primary unit PU. The ground potential on conductor 162, of course, serves also to mark the director selector engaged.

Dial tone

65 With release relay 403 operated, current

from the common dial-tone transformer 531, shown in the lower left-hand corner of Fig. 5, is transmitted back to the calling line by way of the current-limiting condenser 522, contacts of relay 533, conductor 451, wiper 423 in first position, contacts of relay 404, armature 415, conductor 160, and thence to the calling line by way of the upper conductor thereof. The tone delivered by way of the above-traced circuit is of predetermined characteristics, and it indicates to the calling subscriber that he may now operate his calling device in accordance with the digits in the desired number.

80

Dialling the number 45-1234

Upon hearing the above-described dial tone, the calling subscriber manipulates his dial in accordance with the digits in the desired number. When the first digit 4 is dialled, four interruptions are produced in the circuit of line relay 402 of the director, with the result that relay 402 deenergizes four times momentarily. The slow-acting release relay 403 does not fall back at this time as its circuit is only momentarily interrupted. Each time line relay 402 falls back, it closes a circuit for the operating magnet 507 of the register A-T, Fig. 5. This circuit includes the slow-acting series relay 404, distributing wiper 425 and its first contact, and conductor 466. By the operation of magnet 507, the wipers 509-512 are advanced step-by-step until they come to rest on the fifth off-normal set of bank contacts. Relay 404 responds to the first impulse of current delivered to its winding, and it remains operated throughout the series of impulses. At its inner armature, relay 404 opens the above-described dial-tone connection, and at its lower armature it closes a circuit for operating magnet 421. Magnet 421 operates preparatory to advancing the wipers 423-425, but the advance of these wipers does not take place until relay 404 falls back upon the termination of the series of impulses, at which time the wipers 423-425 advance one step. Wiper 423 opens an additional point in the dial-tone circuit when it advances off the first contact; wiper 424 prepares a special start circuit by way of conductor 495, which is not completed except when the first digit dialled is 0; and wiper 425 shifts the operating conductor from the magnet of register A-T to the magnet of register B-U.

105

110

115

120

125

130

When the calling subscriber dials the second office digit 5, five impulses of current are delivered to magnet 513 of the register B-U, resulting in five operations of magnet 513 to advance the wipers 515-517 five steps. Relay 404 responds again as above pointed out to advance the input-control switch ICS one step, advancing the operating circuit from the magnet of the register B-U to the magnet of the register TH.

5 In a similar way, the registers TH and H are operated to record the thousands digit 1 and the hundreds digit 2, the input-control switch ICS being advanced one step at the end of each digit, until its wipers now stand upon the fifth set of bank contacts.

10 As will be explained hereinafter, the registers A-T and B-U have by this time controlled the setting of the translator switch TS. These registers have been released in position 4 of the switch ICS by relay 483, so that, having recorded and disposed of the A and B digits, they are now in normal position in readiness to record the tens and 15 units digits. As a result, the impulses in the tens digit are transmitted to the magnet of the register A-T by way of conductor 466, wiper 425 being at this time on its fifth bank contact. The sixth and last series of 20 impulses is transmitted through the sixth contact in the bank of wiper 425 and over conductor 467 to the register B-U.

Setting the translator switch

25 As soon as the two office-designating digits 4 and 5 have been recorded on the first two registers A-T and B-U, respectively, the translator switch TS may be set in a position to correspond to the composite setting of 30 these two registers, which operation is accomplished by starting the translator switch TS to operating in a buzzer-like manner to advance the wipers 1 to 8 over the sets of 35 contacts successively and by stopping the operation of the translator switch when the translation-stop relay 533 is able to operate in a circuit including wipers 1 and 2 in series, and controlled by wipers 512 and 517 of the 40 first two registers, respectively.

45 As soon as wiper 424 of the control switch ICS is advanced onto its third bank contact at the end of the transmission of the second digit, conductor 460 is grounded, thereby completing a circuit through any one of the 50 first nine off-normal contacts in the bank of wiper 10 and the said wiper for operating magnet 535 of the translator switch TS. This circuit includes contacts of relays 533 and 534. At the same time, a branch circuit 55 is closed for interrupter relay 534 in series with resistance element 536, but relay 534 does not operate for the time being because it is shunted by contacts of magnet 535. When magnet 535 operates, it removes the 60 shunt from around the winding of relay 534, enabling relay 534 to operate and to open the circuit of magnet 535. Magnet 535 thereupon falls back and again shunts relay 534, whereupon relay 534 falls back and again 65 connects up the operating magnet. This operation is repeated over and over, advancing the wipers 1 to 8 of the translator switch TS in a buzzer-like manner over the bank contacts. The two lower contacts in each set 70 (the contacts wiped over by test wipers 1

and 2) are cross-connected on the intermediate distributing frame IDF to the terminals of the conductors extending from the contacts in the banks of wipers 512 and 517. Bank contact set 538 is assigned to office 45. 70

As a result, the contact in this set engaged by wiper 2 is cross-connected by a jumper to the terminal connected with the fourth off-normal contact in the bank of wiper 512, and the lower terminal in set 538 is cross-connected to the terminal on the right-hand side of the distributing frame IDF to which the fifth contact in the bank of wiper 517 is connected. As a result, when the wipers 1 to 8 arrive upon the bank contact set 538 (45), a circuit is completed from ground by way of the grounded wiper 512 and the fourth associated off-normal contact, a jumper on the frame IDF, the next to the last contact in set 538, wipers 2 and 1, the bottom contact in set 538, the lower indicated jumper on the frame IDF, the fifth off-normal contact in the bank of wiper 517 and the said wiper, and the translation-stop relay 533 to battery. Upon operating, relay 533 locks 90 itself at its inner-lower armature to ground over conductor 452 and through armature 416 of release relay 403; it opens the operating circuit of the translator switch TS so as to stop the switch on contact set 538, at armature 552; it grounds wipers 505 and 506 at its upper armature; disconnects conductor 451 from the dial-tone transformer 531 and connects it to ground at its lower armature; and at its upper armature it grounds the first 95 six contacts in the bank of wiper 503 of the output-control switch OCS so as to supply ground potential through wiper 505 to start conductor 457 as long as the output control switch OCS is in any one of the first six 100 positions.

Sending out the office code

The translating switch TS has now been positioned on bank contact set 538 under the control of wipers 512 and 517 of registers A-T and B-U, respectively, and the office code, as determined by the cross-connections on the I.D.F. from the contacts on which wipers 3 to 8 of the translator switch TS are now standing, may be sent out. It will be noted that the contact in set 538, corresponding to office designation 45, on which wiper 3 of the translator switch TS is now standing is cross-connected by means of a jumper to the No. 2 digit-conductor and that the contacts now engaged by the remaining wipers 4 to 8 in contact set 538 are cross-connected to the skip conductor 464. This 110 jumping arrangement insures that with the present setting of the translator switch TS the digit 2 will be transmitted as the first digit in the office code and that no other digits in the office code will be transmitted 115 because the upper five contacts in the set in 120 125 130

use are cross-connected to the skip conductor in order to cause these positions to be skipped in the usual manner, and as will be understood, of course, that the six code-digit wipers 3 to 8 of the translator switch TS provide for a maximum of six code digits to be retransmitted in order to trunk the call to the called office. The full number of these digits is not required ordinarily except when a call is being trunked from an outlying office on one side of the exchange network to an outlying office on the other side of the exchange network. For completing calls from one office to an adjacent office, one or two digits will suffice, three or four digits being used when the call is trunked by way of intervening offices to a called office located an average distance away from the calling office.

Returning now to the point at which start conductor 457 is grounded by the translation-stop relay 533 through wiper 503 of the input-control switch, the placing of a ground potential on start conductor 457 closes a circuit through the motor-driven interrupter 413 for the lower winding of the two-step synchronizing or pick-up relay 412. As soon as interrupter 413 closes, the lower winding of relay 412 is energized, whereupon the relay operates through its first step, closing its first-step inner-upper contacts, thereby closing a locking circuit for itself including both windings in series. No current flows through the upper winding for the time being, however, because the same potential is applied to both terminals.

As soon as interrupter 413 opens, the shunt is removed from around the upper winding of relay 412, whereupon the relay operates fully. At its upper armature, relay 412 transfers the interrupter from the junction of its own windings by way of the middle-upper armature and resting contacts of relay 409 and conductor 474 to the operating magnets 541 of the counting switch CS, and at its lower armature it closes a circuit for the digit-start relay 411, whereupon relay 411 operates and closes a circuit at its lower armature and over conductor 454 for magnet 501 of the output-control switch OCS. Magnet 501 thereupon operates preparatory to advancing wipers 503-506 in a counter-clockwise direction upon its deenergization. At its middle-lower armature relay 411 prepares a circuit for relay 409, which is not closed until all of the digits have been sent out, and at its inner-upper armature it prepares a locking circuit for stop relay 410. At its upper armature, relay 411 removes the shunt from around interrupter 414 (both interrupters are now in their open position) and closes a circuit for reversing relay 408. Relay 408 thereupon operates and shifts the shift conductor 164, an extension of the low-

er outgoing talking conductor 126, Fig. 1, from its previous connection to ground by way of test relay 407 to battery through the associated resistance element; and at its middle-upper armature it shifts conductor 165, an extension of the upper outgoing talking conductor 124, Fig. 1, from its previous connection to battery through the associated resistance element to the free terminal of the interrupter 414. It will be understood, of course, that the operation of relay 412 through its second step, the operation of the digit start relay 411, and the above-described operation of reversing relay 408, all take place responsive to interrupter 413 arriving at open position and before interrupters 413 and 414 arrive in their next closed position. The application of battery potential to conductor 164 in place of the ground potential formerly connected thereto is for the purpose of enabling the control relay of the automatic switch to be controlled properly as will be pointed out hereinafter, and the shifting of conductor 165 from its previous battery connection to ground by way of the interrupter 414 is to enable the impulses to be delivered to the operating magnet of the switch to be operated.

Following the above-described operation of relays 412, 411, and 408, each subsequent closure of the interrupters 413 and 414 results in an impulse being delivered by interrupter 414 over conductor 165 to the operating magnet of the connected switch, and in an impulse being delivered by interrupter 413 over conductor 475 to the operating magnet 541 of the counting switch CS. The effect of the impulses being delivered to the switch train will be considered later. Each time an impulse is delivered to magnet 541 of the counting switch CS, this magnet energizes preparatory to advancing the wipers upon the termination of the impulse. Accordingly, wipers 543 and 544 are advanced one step at the end of each impulse delivered to the switch train and to the counting switch.

When stop wiper 544 is advanced into engagement with its second off-normal contact at the end of the second impulse delivered to magnet 541, it encounters the No. 2 digit conductor on which a ground potential has been placed by way of the contact in group 538 encountered by wiper 3 of the translating switch TS and a jumper on the intermediate distributing frame IDF, wiper 3 being grounded by way of wiper 505 of the output-control switch OCS in position 1. As a result of this, a circuit is closed over the No. 2 digit conductor and through stop wiper 544 of the counting switch for the stop relay 410, Fig. 4. When relay 410 operates, it closes a locking circuit for itself at its inner-lower armature through contacts of the operated relay 411, and at its middle-up-

per armature it opens the circuit of reversing relay 408. Reversing relay 408 thereupon falls back and again connects the conductors 164 and 165 to ground through relay 407 and battery through the associated resistance, respectively. The lower terminal of relay 407 is now grounded independent of interrupter 414 through the inner-upper contacts of relay 408 and the upper contacts of the operated relay 410. It will be understood, of course, that the energization of relay 410 and the deenergization of relay 408 occur while the interrupters 413 and 414 are in their open position following the transmission of the last impulse in the first digit by interrupter 414. The transmission of further impulses by interrupter 414 is prevented now by the shunt around this interrupter through the contacts of relays 408 and 410.

As a further result of the energization of relay 410, the start conductor 457 is opened at armature 433, whereupon pick-up relay 412 falls back. At its inner-upper armature, relay 410 connects conductors 477 and 474 together by way of contacts of relay 409, thereby closing a self-restoring circuit for the counting switch magnet 541 through wiper 543. Magnet 541 now operates in a buzzer-like manner in its self-interrupting circuit over conductors 476 and 474 until it arrives in the normal position shown in the drawings, at which time the operating circuit is opened when wiper 543 passes off the last-grounded bank contact.

When wiper 543 passes off the last-grounded bank contact and opens the self-restoring circuit, the circuit of slow-acting digit-start relay 411 is opened, resulting in the deenergization of this relay after the interval for which it is adjusted. When relay 411 falls back, it opens an additional point in the circuit of reversing relay 408 at its upper armature, at the same time placing an additional shunt around interrupter 414; opens the locking circuit of the slow-acting stop relay 410 at its inner-lower armature; and at its lower armature it removes ground potential from conductor 454, thereby opening the circuit of the operating magnet 501 of the outgoing-control switch OCS. It may be pointed out at this time that ground potential is not removed from conductor 454 at this time in case test relay 407 is held operated over the trunk line extending to any switch in the train, in the event that an operated selector has not yet found an idle trunk, in which case magnet 501 of the output-control switch OCS remains operated until test relay 507 is deenergized over the trunk line, as will be pointed out hereinafter.

When magnet 501 falls back and advances the wipers 503—506 one step, wiper 505 disconnects ground potential from wiper 3 of the translator switch TS and connects

ground potential to wiper 4. Since the fourth to eighth contacts in contact set 538 (on which the wipers 1 to 8 are now standing) are cross-connected by jumpers to skip conductor 464, a self-interrupting circuit is closed for magnet 501 in positions 2 to 6 of wiper 505 by way of conductor 464, and the self-interrupting contacts of magnet 501. Accordingly, magnet 501 operates and advances the wipers 503—506 in a buzzer-like manner until the wipers arrive in seventh position, in which position wiper 505 extends ground potential to wiper 520 of the thousands register TH, on which the thousands digit 1 has been registered. In this position of the outgoing-control switch OCS, ground potential is supplied to start conductor 457 by wiper 503 through wiper 523 of the hundreds register H and any associated off-normal contact.

Retransmitting the numerical digits

When the stop relay 410 falls back after the interval for which it is adjusted and following the restoration of relay 411, it again extends the grounded start conductor 457 to the two-step pick-up relay 412, with the result that pick-up relay 412 is operated through its first step by interrupter 413 and operates through its second step in the hereinbefore described manner when interrupter 413 again opens. Following the operation of relay 412, the transmission of the thousands digit 1 is started, with relays 411 and 408 operated as hereinbefore pointed out.

When the wipers of the counting switch are advanced one step at the end of the first impulse transmitted to the switch train, wiper 544 arrives on the contact connected with the first digit conductor, now grounded through wiper 520 of the thousands register TH, on which the digit 1 has been registered. Stop relay 410 operates to terminate the digit in the manner hereinbefore described.

Incidental to the deenergization of relay 411, when the counting switch CS has been restored to its normal position responsive to the operation of relay 410, magnet 501 of the output-control switch OCS, which was operated over conductor 454 upon the energization of relay 411, falls back and advances the wipers of the output-control switch an additional step preparatory to retransmitting the hundreds digit.

Following the retransmission of the hundreds digit 2, stored on the hundreds register H, the output-control switch OCS is advanced to position 9, in which position ground potential is extended to wiper 511 preparatory to retransmitting the tens digit 3, stored on register A—T, and the output-control switch OCS is advanced to position 10 at the end of the transmission of the tens digit, preparatory to the retransmission of the units digit 4, stored on register B—U. With wiper 505

- in position 10, ground potential is extended to relay 539, which operates and extends ground potential to digit wiper 515 preparatory to operating the stop relay 410 at the end 5 of the units digit. Wiper 516 is maintained normally disconnected from conductor 470 so as to avoid a premature grounding of this conductor by way of whichever digit conductor wiper 516 happens to be standing on.
- 10 With conductor 470 grounded responsive to wiper 505 arriving at position 10, a circuit is prepared for the test-start relay 409, which is closed through the middle-lower armature of the digit start relay 411 and through armature 431 as soon as stop relay 410 operates at the end of the units digit. Upon operating, relay 409 at its inner lower armature locks itself operated through the inner-lower contacts of the operated release relay 403; opens 15 a point in the circuit of the repetition-control relay 406 at its middle-lower armature; opens the branch holding circuit for the magnet of the output-control switch OCS at its lower armature; opens an additional point in the 20 circuit of reversing relay 708 at its upper armature; and at its inner-upper armature it transfers the impulse circuit from the operating magnet of the counting switch CS to stop relay 410. As a result, when pick-up relay 25 412 is again operated, no impulses are delivered to the operating magnet of the counting switch CS; but, instead a single interruption is produced in the circuit established through test relay 407 and over conductor 164, as will 30 be hereinafter explained, following which stop relay 410 is operated to introduce a pause before the next open impulse is transmitted. The impulses transmitted following the operation of the test-start relay are impulses for 35 the purpose of driving the sequence switch of the connector in use (the sequence switch SE, Fig. 3, for example) through its third and fourth positions, as will be explained herein-after.
- 40
- 45 *Trunking the call to the desired office*
- Returning now to the point at which the director operates to send out the single office-code digit 2, it will be recalled that the two 50 closed impulses constituting this digit are sent out by interrupter 414 over conductor 165, while the reversing relay 408 is operated, and while conductor 164 is connected to battery by way of the operated upper armature 55 of relay 408 and the associated resistance element. Responsive to these two impulses, which are transmitted by way of conductor 165, wiper 158, inner-upper armature of the operated relay 116, and conductor 124, vertical magnet 178 operates to raise the wipers 179—181 step-by-step until they come to rest opposite the second level of bank contacts. Off-normal contacts 170 and 177 close upon the first vertical step of the switch, off-normal 60 contacts 177 prepare a circuit for rotary mag-

net 174 and for release magnet 175, while off-normal contacts 170 prepare a circuit for the lower winding of the two-step change-over relay 171. Relay 171 does not operate for the time being because there is no ground potential applied to conductor 126 at this time; rotary magnet 174 does not operate at this time because its circuit is open at the middle-upper armature of relay 171, and the release magnet 175 does not operate at this time because its circuit is held open at the upper armature of relay 171, which first-step upper armature of the relay is operated responsive to current flowing through the relatively inefficient upper winding of the relay over the grounded incoming release-trunk conductor 125.

When reversing relay 408 of the director falls back responsive to the energization of stop relay 410 at the end of the transmission of the code digit 2, it shifts conductor 165 from the impulse circuit to battery by way of the associated resistance element and it shifts conductor 164 to ground through test relay 407, the circuit to ground being completed momentarily through the inner-upper contacts of relay 408 and the upper contacts of relay 410, and subsequently to the upper contacts of relay 411. The application of battery potential to conductor 165 has no particular effect at this time, but the application of ground potential to conductor 169 through relay 407 results in the operation of relay 407 and in the operation of change-over relay 171 of the office selector OS through its second step, as the lower winding of this relay is connected in series with test relay 407 by way of off-normal contacts 170. Relay 407 in the director prepares certain circuits, and momentarily closes a holding circuit for the operating magnet of the output-control switch OCS, but this has no effect upon the normal operation of the system, as will be explained subsequently.

In the office selector OS, when change-over relay 171 operates, it locks itself to the lower talking conductor 126 at its lower armature, independent of off-normal contact 170; prepares a circuit for the upper winding of switching relay 172 at its inner-upper armature; and at its middle-upper armature it completes a circuit through contacts of release magnet 175 for the self-interrupting rotary magnet 174. Magnet 174 thereupon operates in a buzzer-like manner to advance the wipers 179—181 over the bank contacts in the selected level, which operation continues until an idle trunk line (characterized by the presence of a battery potential on the test contact thereof) is found. When an idle trunk line is reached, which trunk line it will be assumed is the one comprising conductors 185 and 187 and extending to the called exchange whereat it terminates in the incoming selector repeater or thousands selector TH.S, Fig. 2, the upper winding of switch-

ing relay 172 is energized in series with resistance element 186 by way of test wiper 180. Relay 172 thereupon operates and closes a locking circuit for itself to the incoming lease trunk conductor 125 at its inner-lower armature; opens the circuit of rotary magnet 174 and an additional point in the circuit of release magnet 175 at its inner-upper armature, thereby stopping the rotary movement and preventing a premature operation of the release magnet; disconnects the incoming release trunk conductor 125 from the upper winding of relay 171 at its middle-lower armature and extends it to wiper 180, thereby applying a ground potential to the multiple test contacts of the seized trunk to mark the trunk line engaged; and at its upper and lower armatures it disconnects the incoming talking conductors 124 and 126 from vertical magnet 178 and the lower winding of change-over relay 171 and extends them by way of wipers 179—181 to the trunk line conductors 185 and 187. When this occurs, relay 171 falls back, as does test relay 407 in the director. It will be understood, of course, that this hunting operation is completed before the slow-acting relays 411 and 410 have had time to fall back one after the other in the course of their inter-digit timing operation.

In the incoming selector TH.S, Fig. 2, the oppositely polarized relays 201 and 202 are included in a bridge across conductors 185 and 187 in series with the high resistance element 207. Current, therefore, flows in a loop circuit over conductors 185 and 187 and through these relays, as well as through the test relay 407 of Fig. 4. Relay 407, being marginally adjusted, does not operate at this time because of the current-limiting effect of resistance element 207; impulse relay 202 does not operate at this time because of the direction in which it is polarized; but relay 201 operates and closes a circuit through contacts of change-over relay 205 for release relay 204. When thus operated by holding relay 201, relay 204 prepares a circuit for switching relay 206 at its upper armature; prepares a circuit for change-over relay 205 at its inner-lower armature; and it opens a point in the circuit of release magnet 214 at its lower armature.

Operating the incoming thousands selector-repeater TH.S

Following the sending out of the single code digit 2, which effects the trunking of the connection to the desired office by way of the trunk line extending to the thousands selector TH.S, the director retransmits the stored thousands digit 1, as hereinbefore pointed out. It will be recalled that reversing relay 408 in the director is operated just prior to the sending out of any digit, being operated at the upper contacts of relay 411 during the open period of interrupters 413 and 414 re-

sponsive to the operation of relay 411 when pick-up relay 412 operates fully upon its upper winding being brought into play by interrupter 413 coming into open position. It will be recalled also that reversing relay 408 shifts the connection of conductor 164 from ground to battery and shifts the connection of conductor 165 from battery to the now-open, ground-impulsing interrupter 414. When this occurs, the current-flow in the bridge across conductors 185 and 187 at the thousands selector TH.S, Fig. 2, ceases, and relay 201, therefore, falls back. Upon falling back, relay 201 opens the circuit of the slow-acting release relay 204 and closes a circuit for change-over relay 205 by way of the inner-lower armatures of relay 204 and 203 and the resistance element 215. Relay 205, however, does not operate at this instant because it is short circuited by ground potential applied to its lower terminal through the back contacts of relay 202 and its own middle-lower armature.

Following the above-mentioned operation of reversing relay 408 of the director, interrupter 414 operates to retransmit the impulses (in this case a single impulse corresponding to the digit 1) in the thousands digit. Each time the interrupter 414 closes, current flows over the established loop to the thousands selector TH.S and including conductors 185 and 187. Impulse relay 202 responds to each closure of the interrupter 414. Each time it responds, impulse relay 202 closes a circuit for vertical magnet 212 by way of the upper armatures of relays 205 and 206, relay 205 responding at the beginning of the first operation of relay 202 when the shunt is removed from around its winding at the back contact of the armature of relay 202. Vertical magnet 212 responds by raising the wipers 216—218 step-by-step until they come to rest opposite the desired level of bank contacts (in this case the first level). In addition to completing the vertical-magnet circuit at its upper contacts, change-over relay 205 shifts the circuit of release relay 204 so that the release relay is in multiple with the vertical magnet during impulsing and is thereby prevented from falling back, as it receives an impulse each time the vertical magnet does. Change-over relay 205 also opens a point in the path over which it was shunted by back contacts of relay 202 just prior to its operation, so that it is not shunted by relay 202 during impulsing.

At the end of the digit being transmitted, reversing relay 408 in the director falls back responsive to the opening of its circuit at the middle-upper armature of stop relay 410. When this occurs, current-flow in the normal direction is resumed over the talking conductors extending to the switch train, and holding relay 201 reoperates. When it

does so, relay 201 opens the circuit of change-over relay 205, whereupon change-over relay 205 falls back and again shifts release relay 204 into connection with the front contact of the armature of relay 201, reestablishing the normal holding circuit of relay 204. The lower winding of battery-feed relay 203 is now energized through the front contacts of relay 201, the lower right-hand repeating-coil winding, lower contacts of relays 205 and 206, off-normal contacts 209, and resistance 215. Relay 203, therefore, operates and closes the self-interrupting rotary-magnet circuit for rotary magnet 213 at its lower armature, which circuit includes off-normal contacts 210, inner-lower armature of switching relay 206, and contacts of release magnet 214. Magnet 213 accordingly operates in a buzzer-like manner to advance the wipers 216-218 across the bank contacts in the selected level in search of an idle trunk line. Relay 203 also shunts the high-resistance element 207 at its upper armature, increasing the current flow over the loop including conductors 185 and 187 sufficiently to operate the marginal test relay 407 in the director.

When an idle trunk line is reached, which trunk line it will be assumed is the one comprising conductors 219-221 and extending to the hundreds selector HS, the upper winding of switching relay 206 is energized through test wiper 217 and over conductor 220, in series with resistance element 273, which is shunted around the upper winding of the two-step change-over relay 271 in order to provide a fast-energizing circuit for relay 206. When relay 206 operates, it opens the rotary-magnet circuit and closes a locking circuit for its lower winding at its inner-lower armature; shunts its own upper winding at its inner-upper armature so as to apply a guarding ground potential directly to the test contact; and at its upper and lower armatures disconnects vertical magnet 212 and the lower winding of battery-feed relay 203, respectively, and connects up wipers 216 and 218. When this occurs, battery-feed relay 203 falls back and again inserts the high resistance element 207 in the bridge across incoming conductors 185 and 187, whereupon marginal test relay 407 in the director falls back. The two-step change-over relay 271 in the hundreds selector HS pulls up through its first step and opens a point in the circuit of release magnet 275 responsive to the upper winding of relay 206 being shunted at the inner-upper contacts of the relay, as above pointed out.

When the sending loop is opened in the director as hereinbefore described just prior to the transmission of the first impulse in the hundreds digit, relay 201 falls back and again closes a circuit for the shunted change-

over relay 205 through resistance element 215, with the result that relay 205 operates responsive to the shunt being opened at the back contacts of relay 202 at the beginning of the first impulse in the hundreds digit. With relay 205 operated, and with relay 206 operated, each impulse in the hundreds digit is transmitted through wiper 216 and by way of trunk conductor 219 to the vertical magnet 278 of the hundreds selector HS. By this operation of the hundreds selector HS, the wipers 279-281 are raised step-by-step until they come to rest opposite the second level of bank contacts (the hundreds digit being a 2). Off-normal contacts 270 and 277 close as soon as the selector is raised from its normal position, and off-normal contacts 270 connect the lower winding of relay 217 to the lower talking conductor 221.

When, at the end of the hundreds digit, the current-flow over conductors 185 and 187 is resumed in the normal direction and relay 201 pulls up, change-over relay 205 falls back responsive to its circuit being opened at the contacts of relay 201 and it again connects the lower winding of battery-feed relay 203 to conductor 221 by way of wiper 218. When this occurs, relays 203 and 271 energize in series over conductor 221, and relay 203 shunts the high-resistance element 207, permitting the marginal-test relay 207 in the director to operate.

In the hundreds selector HS, when relay 271 operates in series with the lower winding of relay 203, it closes a locking circuit for itself at its lower armature independent of off-normal contacts 270; prepares a test circuit for the upper winding of relay 272 at its inner-upper armature; and at its middle-upper armature completes the self-interrupting circuit for rotary magnet 274. Rotary magnet 274 thereupon operates in a buzzer-like manner to advance the wipers 279-281 step-by-step over the contacts in the selected level. When an idle trunk line is reached, which trunk line it will be assumed is the one comprising conductors 285-287 and extending to the connector C, Fig. 3, the upper winding of relay 272 is energized through test wiper 280 and over release-trunk conductor 286, in series with the lower winding of release relay 301. Relay 272 thereupon operates and closes a locking circuit for its lower winding at its inner-lower armature; disconnects the incoming release-trunk conductor 220 from the upper winding of relay 271 and extends it by way of contacts of release magnet 275 to test wiper 280; and at its upper and lower armatures disconnects the incoming talking conductors 219 and 221 from vertical magnet 278 and the lower winding of relay 271 and connects them by way of wipers 279 and 281 to conductors 285 and 287 extending to the connector C. When this occurs, relay 271

of the hundreds selector HS and relay 203 of the thousands selector TH.S, whose lower windings have been maintained energized in series over conductor 221, fall back. When relay 203 falls back, it re-inserts the high resistance element 207 in the bridge across conductors 185 and 187, whereupon the marginal test relay 407 in the director falls back to indicate that an idle trunk line has been found.

In the connector C, it will be noted that the right-hand terminal of the vertical magnet 204 is normally connected to battery by sequence-switch wiper-arm 310 in position 1, and that the other terminal of vertical magnet 204 is normally connected to incoming conductor 285. As a result, when the three impulses constituting the tens digit 3 are delivered from the impulse relay 202 of the thousands selector TH.S by way of conductors 219 and 285 and through wipers 216 and 279 to vertical magnet 204 of the connector C, vertical magnet 204 responds to each of the three impulses and raises the wipers 315-317 step-by-step until they arrive opposite the third level of bank contacts. Off-normal contacts 309 and 307 close as soon as the wipers of the connector are raised from their normal position, and off-normal contacts 307 close a point in the circuit of release magnet 308, but release magnet 308 does not operate at this time as its circuit is maintained open at the inner-lower contacts of release relay 301. Off-normal contacts 306 are opened as soon as the wipers are raised from normal position, and they open the connection between the lower winding of relay 301 and the incoming grounded release trunk conductor 286. Release relay 301, however, remains operated through its inner-upper contacts and through both of its windings in series.

When the lower winding of the battery-feed relay 203 is again connected up in the thousands selector TH.S at the lower contacts of relay 205, upon relay 205 falling back at the end of the digit, current flows through the lower winding of battery-feed relay 203 and over the lower conductor of the established connection to the connector C and thence to battery by way of off-normal contacts 309, operating magnet 311 of the sequence switch SE, and the associated high-resistance element to battery. The marginally-adjusted battery-feed relay does not operate at this time because of the current-limiting effect of the high-resistance element 318, but the operating magnet 311 of the sequence switch SE operates and advances the wipers 310 and 313 from position 1 to position 2, wiper 310 shifting battery potential from the vertical magnet to the rotary magnet.

When the four impulses of the units digit are transmitted to the connector over con-

ductor 285, they pass through the rotary magnet 305 and sequence-switch wiper-arm 310 in position 2 to battery, operating rotary magnet 305 four times to step the wipers 315-317 into engagement with the fourth set of bank contacts in the selected level, the bank contacts to which the line of substation B is connected by way of conductors 321 and 322.

Testing the called line

75

The operating magnet 311 of the sequence switch SE is deenergized at the beginning of the transmission of the units digit when holding relay 201 in the thousands selector TH.S falls back and opens its circuit. Therefore, when magnet 311 energizes again responsive to the operation of holding relay 201 at the end of the units digit, it advances the wiper arms 310 and 313 of the sequence switch SE from position 2 to position 3, the busy-test position. At this point a test is made to determine whether or not the called line is busy, and a subsequent test is made to determine whether or not the called line is disconnected from its terminals, in case it does not test busy, following which the connection to the line is completed and ringing current is applied if the second test made indicates that the line is connected to its terminals in the connector bank.

The called line tests busy

When the wipers 310 and 313 of the sequence switch SE are advanced into third position in the manner above described, wiper 310 prepares to shunt the high-resistance element 318 by way of contacts of test relay 302. At the same time, wiper 313 of the sequence switch SE connects the upper winding of test relay 302 to the test conductor 323 of the called line by way of wiper 316. Therefore, if there is a ground potential on conductor 323 (applied either through another connector having access to the line or through the line-switch individual to the line) because the line of substation B is engaged, an operating circuit exists for the battery-connected upper winding of relay 302, and relay 302 operates, thereby placing a shunt around the high-resistance element 318 so as to permit sufficient current to flow through magnet 311 and over the lower-talking conductor to operate the marginally-adjusted battery-feed relay 203 of the thousands selector TH.S. When battery-feed relay 203 operates at this time, it shunts the high-resistance element 207 in the bridge across the incoming talking conductors 185 and 187, permitting the test relay 407 in the director to operate. This operation of relay 407 occurs at the same time that the output-control switch OCS, Fig. 5, is driven into eleventh position, following the retrans-

119

120

121

122

123

mission of the units digit. With the output-control switch in position 11, and with test relay 407 energized, a characteristic switch-through circuit is completed over conductor 161 to the primary unit PU as soon as stop relay 410 falls back following the de-energization of relay 411. This circuit extends from ground by way of the grounded wiper 505 of the output-control switch OCS in position 11, resistance element 525, conductor 465, lower contacts of relays 410 and 407, conductor 161, wiper 154 of the director selector DS, armature 145, and the lower windings of relays 114 and 113, to battery. 5

15 The marginally-adjusted relay 114 does not operate at this time on account of the current-limiting effect of resistance 525. Relay 113, however, operates and closes a locking circuit for its upper winding to locking conductor 147, grounded at the inner-upper contacts of release relay 112; removes ground potential from release trunk conductor 125 extending to the office selector OS at its armature 148; disconnects battery-feed relay 117 from the intermediate section of the talking conductors at its upper armature and at armature 138, so as to prevent relay 117 from becoming connected up; opens an additional point in the test circuit of the 20 director selector DS at its inner-lower armature; completes the busy-tone circuit at armature 139; and at armature 149 opens the circuit of the director-selector switching relay 116. Relay 116 now falls back and disconnects wipers 152—158 of the director selector DS, thereby freeing the director and permitting it to restore to normal position in a manner to be explained hereinafter. Relay 116 also again connects up line relay 111 to the incoming talking conductors 106 and 108, permitting line relay 111 to operate over the calling line and close a holding circuit for release relay 112. Busy-tone current is now supplied to the calling line over the common busy-tone conductor 167 and through armatures 143 and 139 to the lower talking conductor, by way of the resting contact and armature 55 137, and talking condenser 119.

Upon hearing the busy tone thus supplied to his line, the subscriber at substation A is expected to replace his receiver to permit the relays in the primary unit PU to restore 60 responsive to the deenergization of relays 111 and 112.

The connection established by way of the switches OS, TH.S, and HS to the connector C is released responsive to the falling back of relay 116, and to the operation of armature 148 of relay 113, as conductors 124—126 are now completely disconnected. The way in which the release of the operated switches is accomplished will be explained hereinafter. 65

The called line disconnected

It will now be assumed that the called line has been disconnected from the connector-bank terminals, as for example when a new number has been assigned to the called line. In this case, no ground potential is encountered by test wiper 316 and test relay 302 does not operate to relay back the above-described busy indication in position 3 of the sequence switch SE. Accordingly, the director is not disconnected for the time being and an additional impulse is transmitted by the director to advance the sequence switch SE from position 3 to position 4, as will now be pointed out. 70

It has been pointed out hereinbefore that test-start relay 409 is operated through contacts of relays 410 and 411 when relay 410 energizes at the end of the units digit and while the output-control switch OCS, Fig. 5, is in position 10, and that relay 411 falls back after a slight interval to permit the advance of the output-control switch OCS from position 10 to position 11 to permit the herein-before-described busy test to be performed. Now, when this test does not indicate a busy condition of the called line, as evidenced by the failure of test relay 407 to operate while the output-control switch OCS is in position 11, the two-step pick-up relay 412 is again operated through the interrupter 413 following the deenergization of stop relay 410. Pick-up relay 412 operates through its second step just as interrupters 413 and 414 arrive in open position. Relay 411 operates responsive to the closure of the lower contacts of relay 412 at this time and removes the shunt from around the now-open interrupter 414 in the usual manner. Relay 411, however, does not bring about the operation of reversing relay 408, as relay 409 has been operated. Removing the shunt from around the interrupter 414 while it is in open position opens the circuit which has been previously established through test relay 407 and over the two talking conductors in series for holding relay 201 in the thousands selector TH.S, Fig. 2. Relay 201 falls back at this time and opens the circuit previously established over the lower talking conductor for the operating magnet 311 of the sequence switch SE in the connector C. Magnet 311 thereupon falls back preparatory to again advancing the wipers 310 and 313. 80

In the director, interrupters 413 and 414 close again after a very slight interval, and interrupter 414 again closes the loop circuit through holding relay 201 of the thousands selector TH.S. Relay 201 reoperates and closes the operating circuit over the lower outgoing talking conductor for the operating magnet 311 of the sequence switch SE. Magnet 311 thereupon operates and advances the wipers 310 and 313 into fourth position. 85 90 95 100 105 110 115 120 125 130

Wiper 310 places a shunt around the high-resistance element 318 so as to relay back to a disconnected-line indication to the director, but wiper 313 connects test wiper 316 of the connector to the grounded lower winding of test relay 302 so as to operate test relay 302 in series with the usual cut-off relay associated with the called lineswitch in case the line is not disconnected, and thereby remove the shunt from around resistance 318. In the present case, however, the line is assumed to be disconnected, and test relay 302 does not operate.

With test relay 302 non-operated in position 4 of the sequence switch SE, the shunt placed around the resistance element 318 permits sufficient current to flow over the lower talking conductor to operate the marginally-adjusted battery-feed relay 203 of the thousands selector TH.S to shunt the resistance element 207 and permit the marginally-adjusted test relay 407 of the director to operate.

In the director, while the above-explained operations have been taking place responsive to interrupter 414 arriving in closed position, the stop relay 410 has operated responsive to interrupter 413 arriving in closed position, and in a circuit including the upper armature of the operated relay 412 and the inner-upper armature of the operated relay 409, and has opened the switch-through circuit at its lower armature so as to prevent it from being completed at the lower armature of relay 407 until the output-control switch OCS has been advanced into position 12.

When stop relay 410 operates, it locks itself at its inner-lower armature to ground by way of the contacts of relay 411 in the usual manner, and it opens the circuit of pick-up relay 412 at armature 438. Pick-up relay 412 falls back and opens the circuit of relay 411, with the result that relay 411 falls back after a slight interval and removes ground potential from conductor 454, permitting magnet 501 of the output-control switch to fall back and advance the wipers 503—506 into position 12.

With the output-control switch in position 12, ground potential is supplied by wipers 506 directly to conductor 465, independent of the current-limiting resistance 525. Accordingly, when stop relay 410 falls back after a slight interval, responsive to the opening of its locking circuit at the inner-lower armature of relay 411, it completes a circuit from the now-grounded conductor 465 at its lower contacts and through the lower contacts of the now-operated test relay 407 and over conductor 161 for the lower windings of relays 113 and 114 in series. Relays 113 and 114 both operate at this time and bring about the release of the operated switches and the disconnection of the director in the hereinbefore-described manner. In addition, the marginally-adjusted

relay 114, which operates at this time because the current-flow through its lower winding is not limited by resistance 525, as in the previously-described case, closes a locking circuit for itself at its inner-upper armature through contacts of relays 115, 112, and 110, and at armature 143 it shifts the tone circuit so that a verification tone is sent back from the common conductor 168 to armatures 143 and 139 instead of busy tone, as in the previously-described case.

Upon hearing the verification tone, the calling subscriber is expected to replace his receiver and free the primary units PU and allow it to clear out, and to look in the telephone directory to ascertain that he called the listed number. If he has called the listed number, the calling subscriber is expected to remove his receiver and call the verification operator, to whose position the connection will be completed in a manner to be pointed out hereinafter.

The called line idle

It will now be assumed that the line of substation B is idle when called and that it is not disconnected from the terminals, in which case the advance of sequence switch SE through position 3 and into position 4 takes place as hereinbefore described. With the sequence switch SE in position 4, and with the line of substation A idle, a circuit is closed through the lower winding of test relay 302 by way of wipers 313 and 316 and in series with the cut-off relay of the lineswitch connected to the called line. With test relay 302 operated, resistance element 318 is not shunted by sequence switch wiper 310 in position 4, and the disconnected-line indication is not transmitted back to the director.

In the director, the hereinbefore-described switch-through circuit is not closed over conductor 161 in position 12 of the output-control switch OCS, because the test relay 407 is not in an energized position when stop relay 410 falls back. Under this condition, the de-energization of stop relay 410 is followed by the connecting up and by the operation of the two-step pick-up relay 412, responsive to which the digit-start relay 411 is again operated to permit interrupter 414 to produce an additional momentary interruption in the outgoing control loop. Responsive to this interruption, which is repeated at holding relay 201 of the thousands selector TH.S, Fig. 2, operating magnet 311 of the sequence switch SE in the connector C momentarily falls back and then reoperates to advance the wipers 310 and 313 into position 5 to complete the connection to the called line. With wiper 313 in position 5, ground potential is applied directly to wiper 315 to mark the called line engaged. Contact springs 312 and 314 are operated by the well-known cam ar-

angement responsive to the sequence switch SE arriving in position 5. Contact springs 312 complete a connection from the ringing lead 325 to the called line by way of the 5 lower-winding of ring-cut-off relay 303 and wiper 315. At the same time, contact springs 314 complete a ringing-return circuit from ground to the lower conductor of the called line through the lower armature of release 10 relay 301 and wiper 317. Ringing current is now intermittently applied to the called line to signal the called subscriber in the usual manner.

Clearing out the director

15

In the director, stop relay 410 is again operated by interrupter 413, when interrupters 413 and 414 close following the above-mentioned interruption in the outgoing-control 20 circuit with the output-control switch in position 12. Following the operation of stop relay 410, relays 412 and 411 release, and relay 411 opens the circuit of magnet 501 of the output-control switch OCS, permitting 25 this magnet to fall back and advance the wipers of the output-control switch into position 13. With the output-control switch in position 13, a circuit is closed from the grounded wiper 506, through the resistance element 30 526, and over conductor 163, wiper 156, inner-upper armature of relay 116, relay 115, and the upper winding of relay 114, to battery. Since the upper winding of relay 114 has a relatively large number of turns, relay 35 114 energizes over the above-traced circuit notwithstanding the inclusion of the resistance element 526, Fig. 5, in its circuit, but the marginally-adjusted relay 115, which has a relatively small number of turns, is unable 40 to operate because of the current-limiting effect of resistance element 526. When relay 114 operates, it closes a locking circuit for its upper winding at its inner-upper armature and through contacts of the operated release 45 relay 112; connects up the ringing-tone conductor 166 at its lower armature so as to send back a characteristic ringing tone to the calling line to inform the calling subscriber that ringing current is being applied to the called 50 line; prepares a circuit for the answering supervisory relay 110 at armature 140; prepares to send back an impulse of current from the booster battery 122 at its upper armature; opens an additional point in the test circuit 55 of the director selector DS at armature 142; and at armature 141 opens the circuit of the director-selector switching relay 116, whereupon relay 116 falls back and disconnects the wipers 152-158 of the director selector DS. 60 In the director, when the wipers 152-158 of the director selector are cut off, line relay 402 falls back and opens the circuit of the slow-acting release relay 403. Series relay 404 does not operate at this time because 65 wiper 425 is standing on a disconnected con-

tact. After a slight interval, release relay 403 falls back and opens the locking circuit of the test-start relay 409 at its inner-lower armature, opens an additional point in the previously-established dial-tone circuit at 70 armature 415; opens the locking circuit of translation-stop relay 533 at armature 416; and at armatures 434-440 it closes restoring circuits over conductors 441-447 for the output-control switch OCS, the registers A-T, B-U, TH, and H, the counting switch CS, and the input-control switch ICS, respectively. As a result, the above-named mechanisms are operated in a step-by-step manner by the 75 buzzer-like action of their respective stepping magnets until they arrive in normal position. These restoring circuits are opened at off-normal contacts 502, 508, 514, 519, 522, 542, and 422, respectively. Normally, the counting switch CS, is already in the normal position shown in the drawings when the above-described clearing-out operation takes place, but the restoring circuit is provided through the contacts of relay 403 so that it will be 80 effective when the calling subscriber replaces his receiver before the director has finished its operation.

It will be noted that the above-mentioned restoring circuits all include the release-supervisory relay 401. Accordingly, relay 401 85 operates in the restoring circuits as soon as relay 403 falls back, and it remains operated until the last restoring circuit has been opened. At its upper armature, relay 401 re-applies ground potential to conductor 162 so 90 as to maintain the director guarded against seizure until the clearing-out operation has been completed. At its inner-lower armature, relay 401 closes a circuit to any suitable slow-acting alarm device so as to give an 95 alarm signal in case one of the mechanisms fails to return to its normal position and open its restoring circuit, in which case the director is maintained guarded by way of conductor 162 until an attendant has located and disposed of the abnormal condition.

The apparatus in the director is now in the normal position shown in the drawings, and the director is in readiness to be used in setting up subsequent connections.

Answering supervision

Referring again to the connection established to the line of substation B by way of the switching apparatus shown in Figs. 1-3, 120 it may be pointed out that the condition existing during the ringing operation is that the lower winding of battery-feed relay 203 of the thousands selector TH.S is connected in circuit over the lower talking conductor 125 in series with operating magnet 311 of the sequence switch SE of the connector C, but is not energized because of the current-limiting effect of the high-resistance element 318. At the same time, current is being supplied 130

over both conductors incoming to the thousands selector TH.S from the battery-feed relay 117 in the primary unit PU, maintaining the holding relay 201 energized in the 5 thousands selector TH.S, but the battery-feed relay 117 is unable to operate at this time because of the current-limiting effect of the high-resistance element 207.

When the subscriber at substation B responds to the ringing of his bell by removing his receiver, he closes a direct-current bridge across the conductors of his line, thereby permitting the ring-cut-off relay 303 in the connector C to operate. Upon operating, relay 303 closes a locking circuit for its upper winding at its inner-upper armature through contacts of the operated release relay 301 and contacts of the non-operated relay 302; it opens an additional point 15 in the circuit of release magnet 308 at its lower armature; and at its upper and lower armatures it opens the ringing circuit and completes the talking connection between wipers 315 and 317 and the incoming conductors 285 and 287, respectively, at the same time disconnecting conductors 285 and 287 from their local connections in the connector C.

In the thousands selector TH.S, the battery-feed relay 203 now energizes over the called line, as it is now supplying transmitter current to the called line through the selector HS and the connector C. Upon energizing, relay 203 places a shunt around the 30 high-resistance element 207, thereby increasing the current flow over conductors 185 and 187 sufficiently to permit battery-feed relay 117 of the primary unit to operate. Upon operating, battery-feed relay 117 closes a 35 circuit from the grounded conductor 147 and through the upper armature of the unoperated relay 115 and armature 140 for the answering supervisory relay 110. Relay 110 operates and closes a locking circuit for its self at its inner-upper armature to the grounded conductor 147; completes the talking circuit between the calling and called lines by way of condensers 118 and 119 at its upper armature and armature 137, at the 40 same time disconnecting the source of ringing tone at the resting contacts of armature 137; and at armatures 131 and 136 reverses the connection between the incoming conductors 106 and 108 and the windings of line 45 relay 111, thereby reversing the direction of current flow over the calling line. This reversal of the direction of current flow over the calling line is of no particular utility in the present case, but is used in order to control the coin-collect mechanism when a line 50 equipped with a coin box is calling.

In order to control the momentary application of increased current from the so-called booster battery 122 to bring about an 55 operation of the marginally-adjusted meter

M individual to the line of substation A, the answering supervisory relay 110 opens the locking circuit of the slow-acting relay 114 at armature 133, and at armature 132 disconnects the incoming release-trunk conductor 70 107 from ground through the inner-upper contacts of switch-through relay 109 and the upper contacts of release relay 112 and connects it instead through the upper armature of the still-operated relay 114 and resistance 75 121 to the positive pole of battery 122. Battery 122 has a potential more positive than ground potential, increasing the current flow through the marginally-adjusted meter M, as the battery 122 is now in series with the exchange battery. The primary unit PU is maintained guarded against seizure by any other lineswitch by the positive guarding potential supplied by battery 122, and the lineswitch LS is at the same time maintained 80 operated in the usual manner. The meter M responds to the increased current flow and registers the completed connection.

After a slight interval, relay 114 falls back and reconnects the incoming conductor 90 107 to ground potential at the upper contacts of relay 112, disconnecting the booster battery 122. The restoration of relay 114 does not cause the test circuit of the director selector DS through operated magnet 151 to 95 be again completed, as this circuit is maintained open at armature 135 of the answering supervisory relay 110.

The two subscribers may now converse with each other as desired, the talking circuit 100 being outlined by the heavy conductors. Current for the transmitter at the calling substation A is supplied through the windings of line relay 111 of the primary unit PU, and current for the transmitter at the 105 called substation is supplied through the windings of the battery-feed relay 203 of the incoming thousands selector repeater TH.S in the called office.

Releasing the established connection

When the two subscribers have finished their conversation and replaced their receivers, the operated automatic switches are released responsive to the receiver being replaced at the calling substation A. The connector C, however, is not released responsive to the receiver being replaced at substation A in case the subscriber at the called substation B still has his receiver off the hook, being held operated over the called line as will be hereinafter pointed out more particularly.

The called subscriber hangs up first

It will now be assumed that the subscriber at the called substation B is the first to replace his receiver, whereupon battery-feed relay 203 in the thousands selector TH.S falls back and re-inserts element 207 in the bridge across the incoming conductors 185 and 187, decreasing the current flow sufficiently to cause battery-feed relay 117 to fall back. Upon falling back, 5 battery-feed relay 117 opens a point in the initial energizing circuit of the answering supervisory relay 110, but this relay now remains operated by way of its locking circuit including its inner-upper contacts and the 10 inner-upper armature of release relay 112. It may be here pointed out that a similar primary unit may be employed to handle calls coming from the switchboards of P.B.X. operators and the like, wherein the locking circuit of the answering supervisory relay is omitted, permitting standard reverse-battery supervision to be given to the operator's switchboard.

When the receiver is replaced at the calling substation, line relay 111 in the primary unit PU falls back and opens the circuit of release relay 112, permitting release relay 112 to fall back after a slight interval. When it falls back, release relay 112 removes ground 20 potential at its inner-upper armature from conductor 147, permitting the answering-supervisory relay 110 to fall back, and at its upper armature it removes ground potential from the incoming release trunk conductor 25 and from the outgoing release trunk conductor 125. The removal of ground potential from conductor 107 renders the primary unit PU selectable to the other lineswitches having access to it and it permits the line- 30 switch LS to restore to its normal position in the usual manner.

Removing ground potential from the outgoing release trunk conductor 125 renders the trunk line comprising conductors 185 and 40 187 idle to the other selectors, as it removes ground potential from test wiper 180, and it opens the locking circuit of the lower winding of switching relay 172, whereupon switching relay 172 falls back and disconnects wipers 179 and 181 at its upper and lower armatures, and it closes a circuit for release magnet 175 at its inner-upper armature by way of off-normal contacts 177 and the upper contacts of relay 171. Release 45 magnet 175 thereupon operates and brings about the restoration of the wipers 179-181 to their normal position. When the normal position is reached, off-normal contacts 177 open the circuit of release magnet 175. It 50 is to be noted that the incoming release trunk conductor 125 is maintained disconnected while the office selector OS is releasing, so that the completion of the releasing operation, once started, cannot be interfered with 55 by the reapplication of ground potential to conductor 125 at the primary unit PU.

In the thousands selector TH.S, the holding relay 201 falls back, responsive to the lower winding of battery-feed relay 117 of 60 the primary unit PU being disconnected from

the lower talking conductor at the lower contacts of relay 111 upon the falling back of this relay. When holding relay 201 falls back, it opens the circuit of the slow-acting release relay 204 and disconnects ground potential from the lower winding of battery-feed relay 203. Release relay 204 falls back after a slight interval and at its upper armature removes ground potential from the release trunk conductor extending through the thousands selector TH.S and the hundreds selector HS to connector C, permitting switching relays 206, 272, and 301 of the hundreds selector HS and connector C, respectively, to release. Relay 204 of the thousands selector TH.S also closes at its lower contacts a circuit for release magnet 214 through off-normal contacts 210, whereupon release magnet 214 operates and restores the thousands selector TH.S to its normal position. The circuit of magnet 214 is opened at off-normal contacts 210. 70 75 80

In the hundreds selector HS, switching relay 272, upon falling back, closes a circuit at its inner-upper contacts for release magnet 275 through the upper contacts of relay 271, whereupon the selector HS is restored to normal position in the usual manner. 85 90

In the connector C, release relay 301, upon falling back, closes a circuit at its inner-lower contacts for release magnet 308, which thereupon operates and restores the connector C to its normal position in the usual manner. An extension arm on the armature (not shown) of release magnet 308 removes the usual holding dog (not shown) at the sequence switch SE, allowing this sequence switch to restore to normal position. 95 100

The entire connection is now released and the apparatus which was involved therein is in readiness to be used in setting up subsequent connections. 105

The calling subscriber replaces his receiver first

In case the calling subscriber is the first to replace his receiver, the deenergization of line relay 111 in the primary unit PU occurs at a time when battery-feed relay 117 is energized in the primary unit because battery-feed relay 203 is energized in the thousands selector TH.S and has the resistance element 207 shunted. As a result, battery-feed relays 117 and 203 both fall back responsive to the opening of the lower contacts of line relay 111, but their falling back is merely incidental at this time. The clearing-out of the primary unit PU, together with the release of the switches OS, TH.S, and HS, takes place in the manner described hereinbefore. The connector C does not release at this time, however, even though ground potential is removed from its incoming release-trunk conductor 286, as will now be explained: 115 120 125

When release relay 301 falls back at this

time and opens the locking circuit of ring-cut-off relay 303 at its upper armature, ring-cut-off relay 303 does not fall back and close the circuit of release magnet 308 at its inner-lower contacts as in the previous case, but is maintained operated over the calling line, to which its upper winding is now connected by way of the inner-upper contacts of relay 303 and the upper armatures of the now restored release relay 301. A return circuit for the upper winding of relay 303 is provided over the lower talking conductor through the middle-lower armature of relay 303 and the lower armature of release relay 301. Relay 303 is therefore maintained operated over the called line as long as the receiver remains off the hook at the called substation.

When the receiver is replaced at the called substation, relay 303 falls back and disconnects itself from the line at its middle-lower armature and its inner-upper armature, at the same time closing the release magnet circuit at its inner-lower armature to cause the connector C and its sequence switch SE to be released.

It may be pointed out that the connector C is maintained operated as long as the receiver is maintained off the hook at the called substation for the purpose of preventing a false operation of the lineswitch individual to the called line, which would take place otherwise upon the release of the connector C with the receiver off the hook at substation B.

35 *Overflow at the office selector OS*

In order to explain how a digit transmitted to the office selector OS is repeated a number of times in order to perform repeated testings of the desired group of trunks, it will be assumed that the office selector OS has been operated to the third level in the herein before-described manner, and that the director in use is the director shown in Figs. 4 and 5. Upon referring to the previous description of the operation of the office selector OS, it will be noted that the output-control switch OCS of the director, Fig. 5, is standing in position 1 at the time the directing impulses are transmitted from the director to the vertical magnet 178 of the office selector OS. It will be noted also that the operating magnet 501 of the output-control switch OCS is being maintained operated at this time over conductor 454 by the lower armature of the operated digit start relay 411. It will be recalled also from the previous description that the marginal test relay 407 in the director is maintained operated over the lower conductor and in series with the lower winding of the change-over relay 171 of the office selector OS while this selector is searching for an idle trunk line in the selected level, and that

the marginal test relay 407 in the director falls back normally in time to prevent interference with the advance of the output-control switch OCS and responsive to relay 171 being disconnected from the lower talking conductor upon the operation of switching relay 172 of the office selector.

Assuming now that the office selector OS is unable to find an idle trunk line in the selected level, switching relay 172 does not operate and change-over relay 171 remains connected up, holding the test relay 407 in the director so that it cannot release. As soon as the wipers 179-181 have been driven off the last set of bank contacts in the selected level, the release magnet circuit is closed at overflow contacts 176, whereupon release magnet 175 operates and opens the circuit of rotary magnet 174, at the same time closing a locking circuit for itself through the middle-upper armature of relay 171. By the operation of release magnet 175, the wipers 179-181 of the office selector OS are restored to normal position, whereupon the circuit of release magnet 175 is opened at off-normal contacts 177. The release magnet 175 thereupon deenergizes, but the rotary magnet 174 does not start to operate again at this time as its circuit is opened at off-normal contacts 177. Off-normal contacts 170 do not disconnect the lower winding of change-over relay 171 from the lower talking conductor, as these off-normal contacts are shunted by the lower contacts of relay 171. The office selector OS is now in its normal position mechanically, and is in readiness to be reoperated so that it can again test the desired level of bank contacts.

In the director, the slow-acting digit start relay 411 falls back after the interval for which it is adjusted, following the restoration to normal of the counting switch CS, thereby opening at its lower armature the regular operating circuit for magnet 501 of the output-control switch. Magnet 501, however, is maintained operated by an alternative circuit through the armature 481 of the operated test relay 407 and contacts of relay 409, and it cannot, therefore, fall back to advance the associated wipers. Under this condition, when stop relay 410 falls back and again closes start conductor 457 through armature 433 to the pick-up relay to again start the sending operation, the previously-sent digit is repeated. The repetition-control relay 406 is operated through armature 432 of stop relay 410, middle-lower armature of relay 409, and the inner-lower armature of relay 407. Relay 406 places an additional ground potential on the associated branch of conductor 454 at its inner armature, and it closes a circuit for operating magnet 426 of the repetition controller RC. Operating magnet 426 energizes and

advances the control wiper 429 from first position to second position.

When the digit start relay 411 pulls up responsive to its circuit being closed at the 5 lower contacts of pick-up relay 412, at the time the retransmission of the repeated digit is started, it brings about the release of relays 407 and 406 by removing the shunt from around interrupter 414 and closing the circuit 10 of reversing relay 408, in the usual course of the retransmitting operation, but this does not result in an advance of the output-control switch OCS because relay 411 closes the usual circuit over conductor 454 for the magnet of 15 the output-control switch.

When the repeated digit is received by the office selector OS, the wipers are raised step-by-step until they come to rest opposite the desired level of bank contacts, and the wipers 20 are again rotated over the contacts in the level in search of an idle trunk line.

In case a trunk line has become idle in the meantime and is available when it is tested by the wipers of the switch, this trunk line 25 is seized and test relay 407 falls back responsive to the usual operation of switching relay 172. If no trunk line is found during the second test of the trunk line, test relay 407 in the director remains operated following 30 the second retransmission of the digits and the advance of the output-control switch OCS from position 1 to position 2 is again prevented. In addition, a second impulse is delivered in the above-described manner to 35 the operated magnet 426 of the repetition counter, and wiper 429 is advanced from second position to third position.

In case the office selector OS is unable to 40 find an idle trunk in the desired group the third time it is operated, test relay 407 in the director again remains operated with the result that the repetition-control relay 406 is again operated when stop relay 410 falls back, and the repetition counter RC advances 45 from third position to fourth position. In the fourth position of the repetition counter RC, wiper 429 places ground potential directly on conductor 161, operating relays 113 and 114 in the primary unit PU to disconnect 50 the director and give the calling subscriber a verification tone in the manner described hereinbefore in connection with a call to a line which has been disconnected from the connector bank terminals.

55 The repetition counter RC is restored to normal position by the action of its release magnet 427 which is energized through off-normal contacts 428 and over conductor 453 when magnet 501 of the output-control switch OCS falls back responsive to the director being disconnected and to the deenergization of relay 411.

Overflow at the thousands selector TH.S

65 The way in which an overflow condition

at the thousands selector TH.S results in the digit which has been transmitted to the thousands selector being repeated until the repetition counter RC, Fig. 4, operates to cut off the director or until an idle trunk has been 70 found will now be explained. It will be recalled that holding relay 201, upon operating over the incoming conductors 185 and 187 when the thousands selector is seized, applies ground potential to the right-hand 75 terminal of the lower winding of battery feed relay 203 at the same time that it closes a circuit for release relay 204. Battery-feed relay 203 cannot operate at this time because its circuit through the lower right-hand re-peating coil winding, contacts of relays 205 and 206, and the resistance element 215 is maintained open at off-normal contacts 209. Accordingly, relay 203 does not shunt the 80 high resistance element 207 when the thousands selector is seized, and the marginal test relay 407 in the director is permitted to remain in its unoperated condition. It will be recalled also that battery-feed relay 203 85 does not operate during the transmission of impulses to vertical magnet 212 by relay 202, as the holding relay 201 is in restored condition at that time.

When the holding relay 201 is reoperated responsive to current flow being resumed in 90 the normal direction over conductors 185 and 187 at the end of the transmission of impulses to vertical magnet 212, the lower winding of battery-feed relay 203 is operated 95 through off-normal contacts 209 and resistance element 215 to close the self-interrupting circuit of magnet 213 at its lower armature and to shunt the resistance element 207 at its upper armature. Accordingly, while 100 rotary magnet 213 is operating to drive the wipers 216-218 over the contact in the selected level, resistance element 207 is shunted to permit the marginal test relay 407 in the director to operate and thereby prevent the 105 advance of the output-control switch OCS 110 as hereinbefore explained.

Assuming that the wipers 216-218 do not 115 encounter an idle trunk, the rotary movement continues until they have been driven off the last set of bank contacts in the selected level, whereupon the overflow contacts 211 are pressed into engagement with each other, thereby completing a circuit for release magnet 214 through off-normal contacts 210. Release magnet 214 thereupon operates and 120 closes a locking circuit for itself through off-normal contacts, lower contacts of relay 203, and contacts of switching relay 206. By the operation of magnet 214, the thousands selector is restored to its normal position, whereupon off-normal contacts 210 125 open the circuit of release magnet 214, permitting this magnet to deenergize. Off-normal contacts 209 separate, but they do not 130 open the circuit of the lower winding of bat-

tery-feed relay 203 because they are shunted by the inner-lower armature of relay 203 and its working contact. Relay 203 accordingly remains operated and maintains the 5 resistance element 207 shunted, in order to cause the previously sent digits to be re-sent by the director.

It will be understood, of course, that the battery-feed relay 203 is deenergized just 10 prior to the first impulse in the retransmitted digit so as to open a point in the circuit of rotary magnet 223 at its lower armature and thereby prevent an operation of the rotary magnet during the vertical 15 movement.

Overflow at the hundreds selector HS

Upon referring to the hundreds selector HS, it will be noted that the off-normal contacts 270 maintain the lower winding of relay 271 disconnected from the lower talking conductor until the switch is moved from its normal position. Accordingly, the battery-feed relay 203 of the thousands selector TH.S is 25 unable to operate in series with the lower winding of relay 271 until the vertical movement of the hundreds selector has been accomplished in the hereinbefore-described manner and the holding relay 201 has reoperated to apply ground potential to the right-hand terminal of the lower winding of relay 203, whereupon relay 203 operates and the two-step relay 271 operates fully through its lower winding and starts the rotary movement 35 by closing its middle-upper contacts.

In case the hundreds selector HS is unable to find an idle trunk line in the selected level, the closure of the overflow contacts 276 results in an operation of release magnet 275 40 to restore the hundreds selector to normal preparatory to a reoperation of the hundreds selector. The lower winding of relay 271 remains locked to the lower talking conductor at the lower contacts of the relay, notwithstanding the opening of off-normal contacts 45 270.

When the holding relay 201 in the thousands selector falls back just prior to the receipt of the first impulse in the received digit, the lower winding of battery-feed relay 203 and the lower winding of relay 271 are deenergized. Relay 271, being now energized only by its inefficient upper winding, falls back and opens its normally open contacts, but does not close its first step upper contacts, thereby maintaining the circuit of release magnet 275 opened during the next 55 vertical movement.

Following the second vertical movement, the hundreds selector HS either finds an idle trunk or is restored to normal position again as above described. In case the hundreds selector HS is unable to find an idle trunk the third time it searches over the desired bank contacts, the director is automatically discon-

nected under the control of the repetition-counter RC, Fig. 4, with the result as hereinbefore described, including the sending back of the verification tone signal to the calling line. 70

Unequipped selector levels

In most any working automatic exchange, there are a number of unequipped selector levels. In the present case, no special provision need be provided for disposing of calls inadvertently directed to an unequipped selector level, as no selector will cut in on a contact set that does not have a battery connection to the test contact thereof. Accordingly, when a selector is brought to rest opposite an unequipped level of contacts, the wipers are rotated entirely over the contact sets and the selector is released in the hereinbefore-described manner responsive to the closure of the overflow contacts. The director receives the same indication that it receives when a selector rotates over the contacts of a level wherein all trunk lines are engaged, and it consequently repeats the digit previously transmitted to the selector until the director is disconnected responsive to the operation of the repetition-counter RC, Fig. 4. The calling subscriber receives the verification tone as hereinbefore described, and he is, therefore, prompted to verify the called number before dialling it again. 85 90 95

Calling the assistance operator

In order to render assistance to calling subscribers who are unable to obtain desired connections, provisions have been made whereby a subscriber may remove his receiver and dial the digit 0 and obtain connection with the switchboard of the assistance operator, Fig. 6. The way in which this connection is set up will now be explained. 100 105

Assuming that the subscriber at substation A desires to obtain connection with the assistance operator and that his lineswitch LS connects with the primary unit PU, Fig. 1, when the receiver is removed, and that the director selector DS connects with the director shown in Figs. 4 and 5, this director is prepared for operation in the hereinbefore-described manner. 110 115

When the calling subscriber dials the digit 0, line relay 402, Fig. 4, delivers ten impulses by way of series relay 404 and wiper 425 to magnet 507 of the register A-T by way of conductor 466. The wipers 509-512 are advanced step-by-step until they come to rest on the tenth off-normal set of bank contacts. 120

With wiper 510 of the register A-T standing on its tenth off-normal contact, the advance of the wipers of the input-control switch ICS into second position results in the starting of the translator switch TS, whereas the translator switch TS is not started until 130

two digits are received in case the first digit dialled is any other than the digit 0. The starting circuit for the translator switch TS is as follows: from ground, by way of wiper 424 of the input-control switch ICS, the second associated bank contact, conductor 459, tenth off-normal contact in the bank of wiper 510 and the said wiper, armature 552 of relay 532, and contacts of relay 534 to battery by way of operating magnet 535. The operating magnet 535 and interrupter relay 534 interact in the hereinbefore-described manner and magnet 535 is operated to advance the wipers 1 to 8 of the translator switch TS step-by-step until they arrive upon bank contact sets 537, assigned to the digit 0. This is the position in which wipers 1 to 8 are shown in the drawings. When the wipers arrive in this position, a circuit is closed for 20 the translation stop relay 533 as follows: From ground by way of the now grounded wiper 512 and its tenth off-normal bank contact, a jumper on the intermediate distributing frame IDF, wipers 2 and 1 of the translator switch TS, an additional jumper on the intermediate distributing frame IDF, normal contact in the bank wiper 517 and said wiper, and translation stop relay 533 to battery. Relay 533 thereupon operates and stops 25 the advance of the translator switch TS and starts the sending operation in the hereinbefore-described manner. The No. 3 wiper of the translator switch TS is now cross-connected by a jumper on the intermediate distributing frame to the No. 3 digit conductor, resulting in the digit 3 being sent out. The three impulses of this digit are transmitted 30 to the vertical magnet 178 of the office selector OS, and the wipers 179—181 of the office selector OS are thereby raised opposite the third level of bank contacts and are rotated over these contacts in search of an idle trunk line.

In the director, when the output-control switch OCS advances to position 2, which it will not do until the office selector OS has found an idle trunk line in the selected level, it transfers the ground potential from the No. 3 wiper of translator switch TS to the 45 No. 4 wiper, closing a circuit over switching conductor 163 which excludes the current-limiting resistance 526, for relays 114 and 115 in series. The marginally-adjusted relay 115 operates in this circuit and at its inner-upper armature closes a locking circuit for itself and for relay 114 in series through contacts of relays 112 and 110, at the same time opening a point in the locking circuit of relay 114 to prevent relay 114 from shunting 55 the winding of relay 115. Relay 114 is delayed in its operation by the copper collar or slug placed on the armature end of its core, as indicated by the solid black upper portion. When it operates, relay 114 brings about the 60 hereinbefore-described results, including the

disconnection of the wipers 152—158 of the director selector DS to free the director. Relay 115, opens a point at its upper armature in the circuit of answering supervisory relay 110 and prepares a circuit for the switch-through relay 109. 70

Assuming that the trunk line found by the wipers 179—181 of the office selector OS is the trunk line comprising conductors 182—184 and extending to the trunk circuit TC, Fig. 6, 75 the high resistance line relay 601 of the trunk circuit TC, which is bridged across conductors 182 and 184 through contacts of relays 604 and 603, operates over conductors 182 and 184 in series with the windings of the marginally-adjusted battery-feed relay 117 in the primary unit PU as soon as relay 116 falls back to disconnect the director selector 80 wipers and close the trunk line through to the selector OS. Relay 117, however, does not operate at this time because of the high-resistance of the windings of relays 601 in the trunk circuit TC. 85

When relay 601 operates, it closes a circuit for call lamp 605 at its upper armature through contacts of relay 604 and 603, and at its inner-upper armature it closes a circuit for release relay 602. Release relay 602 thereupon operates and prepares a locking circuit for relay 603 at its lower armature, 90 at the same time placing ground potential on the incoming release trunk conductor 183 at its upper armature so as to provide a holding circuit for the established connection after the primary unit PU has switched through, as will hereinafter be explained. 95

When the assistance operator notes the lighted condition of the call lamp 605, she responds by inserting the plug of an idle cord circuit into the jack J, whereupon sleeve relay 604 operates over the sleeve of the jack J and the sleeve of the inserted plug and closes a multiple holding circuit for relay 602 at its inner-upper armature; disconnects the lower winding of relay 601 from the lower talking conductor at its lower armature, permitting line relay 601 to fall back; closes a circuit at its inner-lower contacts for the slow-to-operate relay 603; and at its upper armature it disconnects the incoming talking conductor 182 from the upper winding of relay 601 and connects it to ground through contacts of relay 603. Relay 603 operates after a slight interval and removes the ground connection; closes a locking circuit for itself at its inner-lower armature; and at its upper and lower armatures extends the incoming conductors 182 and 184 to the tip and ring contacts of the jack J. 110

In the primary unit PU, battery-feed relay 117 responds to the momentary connection of ground potential to the upper talking conductor by the above-described action of relays 604 and 603 of the trunk circuit TC. 115 Upon operating, battery-feed relay 117 closes 120

- a circuit from the grounded conductor 147 and through the upper armature of the operated relay 115 for switch-through relay 109. Relay 109 thereupon operates and closes 5 a locking circuit for itself at its inner-upper armature to the release trunk conductor, grounded at the upper contacts of relay 112; and at its upper and lower armatures connects the incoming conductors 106 and 108 10 to the outgoing conductors 124 and 126 independent of the talking condensers, disconnecting the front and back bridges including relays 111 and 117. The operated relays 111, 112, 114, 115, and 117 now all fall back. Relays 112 removes ground from the release trunk conductor of the established connection at its upper armature, but this conductor is now maintained grounded as above 15 pointed out at the upper armature of relay 602 of the trunk circuit TC, Fig. 6. The middle-upper armature of relay 109 is operated to prevent booster battery current from battery 122 being momentarily applied to the release trunk conductor while all three contacts 20 of relay 114 are in engagement as relay 114 falls back.

The calling line is now extended metallically to the tip and ring conductors of the jack J, and the connection is being held intact by 25 release relay 602 of the trunk circuit TC, which is held operated by sleeve relay 604.

The calling subscriber may now converse with the assistance operator, energizing current for the transmitter on the calling line 30 being supplied by way of the operator's cord circuit.

Clearing out the connection to the assistance-operator's switchboard

- 35 The relay circuits within the trunk circuit TC, Fig. 6, are so arranged that the assistance operator may change cord circuits, if need be, without causing the connection to clear out. When the cord circuit first used is removed 40 from jack J, sleeve relay 604 falls back and transfers the incoming talking conductors 182 and 184 to the line relay 601 at its upper and lower armatures, whereupon line relay 601 operates and again closes a holding circuit for release relay 602 at its inner-upper armature. At its upper armature, relay 601 45 closes a circuit through the middle-upper armature of sleeve relay 604 and the inner-upper armature of the operated relay 603 for the hold lamp 606, which lamp is lighted whenever the operator removes her plug before the calling subscriber replaces his receiver to signal the operator of the existing condition. It is to be noted that armatures 50 607 and 608 of relay 603 have separated the inner terminals of the windings of line relay 601 and have connected the upper and lower windings to ground and battery, respectively, in order to provide an operating circuit for 55 relay 601 at the present time.

When the assistance operator reinserts the same plug or another plug into the jack J, relay 604 operates and relay 601, being disconnected, falls back. The hold lamp 606 is 60 extinguished.

Since the conductors of the calling line have been extended metallically into the operator's cord circuit, regular disconnect supervision may be given the operator when the calling subscriber hangs up his receiver.

When the calling subscriber has replaced his receiver and when the operator has removed her plug from the jack J, all of the relays of the trunk circuit TC fall back, and ground potential is removed from conductor 183 at the contacts of relay 602, permitting the connection established to the trunk circuit TC to clear out.

Calling the verification operator

When a calling subscriber has dialled a number and has received the verification tone, and has ascertained that the number dialled is the number listed in the directory, he is expected to call the verification operator and have her inform him whether or not the number has been changed or to give him such other information as may be necessary or desirable under the circumstances. If desired, the assistance operator, a portion of whose equipment is shown in Fig. 6, may serve also as the verification operator. It is more usual, however, for a separate designation to be assigned to a different operator's position for the purpose of verification. The number of the verification operator may consist of only two digits, in which case the translating switch TS, Fig. 5, responds to the setting of the registers A—T and B—U by 90 assuming a position individual to their setting, whereupon the necessary digits are sent out as determined by the cross-connections from the contacts in the banks of wipers 3 to 8 of the translating switch TS. Following the 95 transmission of the last digit in the code necessary to reach the position of the verification operator, the output-control switch OCS applies ground potential to the next succeeding wiper of the translating switch TS, closing a circuit by way of a jumper (not shown) to the switching conductor 163, causing the primary unit PU to prepare to operate relay 109 when the verification operator 100 responds.

Disposing of calls to a non-existent office

Assuming that a subscriber removes his receiver and inadvertently dials the designation of a non-existent office, the registers A—T and B—U are set in a composite position to which no assumed position of the translator switch TS corresponds. As a result, no circuit is closed for the translation stop relay 533 and the translator switch TS 125 continues to hunt. The unassigned office set 130

of contacts, contact sets 536 in the bank of the translator switch, is set aside for disposing of calls to unassigned or non-existent offices. Whenever the wipers 1 and 2 pass over the two lower contacts in set 536, a circuit is closed from the lower contacts by way of wipers 1 and 2, the next lower contact, and conductor 458 for the lower winding of the two-step hunting supervisory relay 405. Relay 405 is thereupon operated to its first step by the current flowing through its lower winding, whereupon it closes a locking circuit for itself by way of its first set of upper contacts. The upper winding is not energized at this time, as it is supplied with the same potential at both terminals.

As soon as the wipers of the translating switch TS have passed off the contact set 536, the hunting-supervisory 405 operates fully and extends conductor 458 to conductor 161. Therefore, when the wipers of the translating switch TS reach the contact set 536 the second time, ground potential is extended over conductor 458 and through the lower armature of the operated relay 405 to the switch-through conductor 161, operating relays 113 and 114 in the primary unit PU. As a result, the director is disconnected and verification tone is sent back to the calling line in the hereinbefore-described manner.

Supervising the primary units

It will be noted that there is a supervisory lamp 120 individual to the primary unit PU. This lamp becomes lighted as soon as the primary unit PU is taken for use and release relay 112 operates. This serves as a signal to an attendant that the primary unit PU is in use. These lamps may be mounted at the end of a row of primary units and in such a position that they may be readily observed.

The lamp 120 continues to be lighted until the called subscriber responds and brings about the operation of the answering supervisory relay 110, whereupon the lamp is extinguished and remains extinguished during conversation.

It will be recalled that relay 113 is operated over wiper 154 of the director selector DS whenever the line called is busy or whenever the connection cannot be completed and verification tone is given. When relay 113 operates, it shifts the circuit of lamp 120 so that it includes the interrupter 123, causing the lamp 120 to flash until the calling subscriber replaces his receiver. The flashing of a lamp such as 120, therefore, indicates to an attendant that the calling subscriber is leaving his receiver off the hook and holding the primary unit PU unnecessarily.

It is to be noted that the circuit of lamp 120 is opened to extinguish the lamp when a call is made to an operator's position, as at this time relay 115 operates and opens the lamp circuit at its lower contact.

Premature dialling

In case a calling subscriber, forgetting or failing to wait for the dial-tone signal, dials the first digit of the desired number before an idle director has been connected up, the searching action of the director selector is stopped, and a verification tone signal is sent back to the calling line, as will now be explained.

Assuming that the director selector DS is searching for an idle director responsive to a call from substation A, for example, if the calling subscriber proceeds to operate his dial while the director selector DS is still searching for an idle director, when the first impulse of the dialled series is received, line relay 111 of the primary unit PU is momentarily deenergized, closing at its inner-lower armature a circuit for relays 113 and 114, by way of contacts on relays 110, 112, 114, and 116. Relay 113 operates and closes a locking circuit for itself at its inner-upper contacts, opens a point in the circuit of relay 116 at armature 149; and at its inner-lower armature opens the circuit of the operating magnet 151 of the director selector DS to stop further hunting. Relay 114 operates to connect the verification-tone conductor 168 to the lower talking conductor at armature 143 by way of armature 139 to indicate to the calling subscriber that he has dialled too soon. He is then expected to replace his receiver and initiate a new call.

What is claimed is:

1. In an automatic telephone system 100 wherein register senders are interposed between calling lines and the automatic switches, means for sending impulses from a register sender directly to the operating magnet of an automatic switch to operate 105 the automatic switch to extend connection to a second automatic switch, and means for extending an operating circuit from the register sender by way of the operated switch directly to the operating magnet of said second switch, whereby the operating magnet of the second switch may be operated directly from the register sender to position the second switch.

2. In an automatic telephone system employing register senders, means in a register sender for registering a plurality of digits, a group of automatic switches, means in said register sender for operating the sending apparatus of the register sender to retransmit a registered digit, a group selector responsive to the sending of said registered digit for extending connection to any idle one of said automatic switches, each of said automatic switches having an operating magnet, and means for again operating the sending apparatus of said register sender to retransmit a further registered digit directly to the operating magnet of the one of said 130

- automatic switches to which the connection has been extended.
3. In an automatic telephone system wherein register senders are interposed between calling lines and the automatic switches, means for sending impulses from a register sender directly to the primary magnet of a selector over one talking conductor, and means in the selector independently controlled from the register sender over the other talking conductor for initiating the operation of the secondary magnet of the selector.
4. In combination, a register sender comprising a variably adjustable digit register and a digit sender operable under the control thereof, a pair of outgoing conductors normally connected to the two poles of the exchange battery, respectively, means for shifting one talking conductor from the first pole to the second pole of the exchange battery and for disconnecting the second conductor from the second pole, and means for thereupon operating said digit sender to connect the second conductor to the first pole of the exchange battery a number of times corresponding to the instant adjustment of said register, the first-named means being thereupon effective to restore said conductors to their previously existing connections with the exchange battery.
5. In a switching system wherein a train of automatic switches is arranged to be operated from a sending device, a circuit loop extending from said sending device to said train of switches, a current source, means for transmitting digits over said loop by sending predetermined series of impulses from said current source and in a given direction to operate the switches in said train, and means for maintaining current-flow over said loop in the opposite direction from said current source between digits in order to exercise incidental control over the switches in said train.
6. In a telephone system, a trunk line, an automatic two-motion selector switch having access to a plurality of groups of trunk lines, a register sender and means for connecting it to the first-named trunk line, means for operating the registering apparatus of said register sender, means for operating the sending apparatus of said register sender to transmit impulses over one outgoing conductor only of said trunk line to said selector switch, said selector switch being responsive to said impulses to select one of the groups of trunk lines accessible thereto, and means controlled from said register sender over the other talking conductor only of the first-named trunk line for initiating the trunk-hunting movement of said selector switch, said selector switch being then effective to hunt for and connect with an idle trunk line in the selected group.
7. In an automatic telephone system, a trunk line, a group of register senders, means for extending a connection from a calling line to said trunk line and for thereupon connecting one of said register senders to said trunk line, means in the connected register sender controlled from the calling line for registering the digits in a desired telephone number, means in said register sender for re-transmitting series of impulses under the control of the said registering means, a train of automatic switches responsive to the re-transmitted impulses for setting up a connection to the desired line and for testing the line, means in the train of switches for indicating in the register sender the condition of the called line as indicated by said testing operation, means in the register sender for recording in said trunk line the indicated condition of the called line, and means in the trunk line for disconnecting the register sender and for giving the calling subscriber any one of a plurality of characteristic signals, depending upon the indicated condition of the called line.
8. In a telephone system as claimed in claim 7, means in said trunk line controlled from said register sender to release the operated train of automatic switches in case the called line tests busy.
9. In a telephone system as claimed in claim 7, means in the trunk line controlled from said register sender for releasing the operated train of automatic switches in case the tests made of the called line indicates that it is disconnected from its terminals.
10. In an automatic telephone system wherein trunk-hunting group selectors are arranged to be operated from a register sender responsive to impulses transmitted thereto to select a group of trunk lines and to then select an idle trunk line in the selected group, means for starting a timing operation in said register sender when a series of impulses has been transmitted by the register sender to a group selector, means in a group selector for indicating in the register sender when it has found an idle trunk line in the selected group, and means in the register sender effective in case the group selector has not found an idle trunk by the time the said timing operation is completed for repeating the said series of impulses.
11. In a telephone system as claimed in claim 10, means in the operated group selector responsive to all of the trunk lines in a selected group testing busy for restoring the group selector to normal position, whereby the group selector responds to the repeated series of impulses to again select the same group of trunk lines.
12. A repeater for controlling the operation of automatic switching apparatus to set up telephone connections, said repeater including a pair of oppositely polarized re-

lays, means for sending impulses of one polarity to said repeater to bring about the operation of said switching apparatus, and means effective while impulses are not being transmitted for maintaining the oppositely polarized relay operated to maintain a holding circuit for the operated switching apparatus.

13. In a two-motion automatic switch having a pair of talking conductors and a release trunk conductor incoming thereto and having primary, secondary, and release magnets for controlling the primary, secondary, and releasing operations, respectively, a two-step change-over relay in said selector, means for taking said selector for use and for operating said change-over relay through its first step to open a point in the circuit of said release magnet, means for sending impulses to the primary magnet of said switch to associate the switch with a desired group of contacts, and means thereupon effective for operating said two-step change-over relay through its second step to initiate the operation of the secondary magnet to drive the switch over the selected set of contacts.

14. In an automatic telephone system, an automatic switch having primary and secondary movements controlled by primary and secondary operating magnets, respectively, means for sending two series of digit impulses to said automatic switch over one talking conductor only, and means including a step-by-step progressively movable sequence switch associated with said automatic switch and having an operating magnet directly controlled over the other talking conductor only for causing the first of said series of impulses to be delivered directly to said primary operating magnet and for causing the second of said series of impulses to be delivered directly to the secondary operating magnet.

15. In an automatic telephone system, a train of automatic switches including a plurality of group selectors and a final connector for extending a connection to a called line, a register sender arranged to send successive series of impulses to said train of switches to bring about their operation to extend the connection to the desired line, and means in said register sender effective after the connection has been extended to the called line for sending additional impulses to the final connector, and means in the final connector for making successive tests of the called line responsive to said additional impulses.

16. In a telephone system as claimed in claim 15, means for transmitting back to the register sender from the final connector the condition of the called line as indicated by the tests made by the final connector.

17. In a telephone system, a trunk line,

register senders, means for extending connection from a calling line to said trunk line and for thereupon taking one of said register senders for use, a train of automatic switches arranged to be operated responsive to impulses transmitted from said register sender to set up a connection to a desired called line, an output-control switch in said register sender arranged to be advanced following each transmitted digit, means for advancing said output-control switch through additional positions following the transmission of the last digit and for making successive tests of the called line at the same time, and means depending upon the instant position of said output-control switch and the condition of the called line for closing a switch-through circuit between said register sender and said trunk line, there being a plurality of switch-through circuits between the register sender and the trunk line, and means whereby the switch-through circuit closed indicates in the trunk line the condition of the called line.

18. In an automatic telephone system wherein the automatic switches are positioned responsive to trains of impulses transmitted thereto from register senders, means effective in case an automatic selector switch is unable to find an idle trunk line in the selected group for restoring the automatic switch to its normal position and for causing the register sender in use to repeat the digit previously transmitted to such switch, a repetition counter in the register sender, means for advancing said repetition counter each time a digit is repeated, and means responsive to said repetition counter being advanced into a predetermined position for stopping the repeating operation and for disconnecting the register sender.

19. In an automatic telephone system wherein the telephone connections are set up by way of primary units through automatic switches to called lines, means in any primary unit responsive to all trunks in a selected group being engaged, responsive to the called line being busy, and responsive to the called line being disconnected from its terminals for releasing the operated automatic switches and for signalling the calling subscriber that he cannot obtain the desired connection.

20. In a telephone system, a trunk line having front and back bridges through which talking current is arranged to be supplied to the calling and called lines of an established connection, respectively, means effective subsequent to said trunk line being taken for use by a calling line for extending a connection from such trunk line to an operator's switchboard and for signalling the operator thereat, and means automatically effective when the operator responds for connecting the calling line metallicly through the said trunk line to the operator's switchboard and for

disconnecting said front and back bridges in the trunk line.

21. In a telephone system, an automatic switch having access to groups of lines, means for operating said switch into association with a desired group of lines, and means for causing said switch to successively test the lines of the selected group a predetermined plurality of times.
- 10 22. In a telephone system, an automatic switch having access to groups of lines by way of movable wipers, means for positioning said wipers in association with any desired one of said groups of lines, and means for causing said switch to move its wipers over the lines in the desired group a predetermined plurality of times.
- 15 23. In an automatic telephone system employing register senders for storing the 20 digits of a wanted number and for controlling

the operation of automatic switches to complete the connection desired, means effective to restore an operated group selector after it has hunted over a desired group and found all lines therein engaged, and means in the 70 connected register controller for causing said selector to hunt again over said groups of lines.

24. In an automatic telephone system, register senders and means for taking an 75 idle one for use temporarily for use in setting up a connection through a plurality of automatic switches, and means for delivering the setting impulses directly to the setting magnets of said switches from the register 80 sender in use.

In witness whereof, I hereunto subscribe my name this 5th day of May, A. D. 1931.

JOHN E. OSTLINE. 85
